8 Claims. (Cl. 260—296)

This invention relates to 3,3-disubstituted-2-amino-4-oxo-3,4-dihydropyridines and the 3,4,5,6-tetrahydropyridine analogs thereof. More particularly, the invention relates to 3,3-disubstituted-2-amino-4-oxo-3,4-dihydropyridine, 3,3-disubstituted-2-amino-4-oxo-3,4,5,6-tetrahydropyridine and acid addition salts of those compounds.

The 3,3-disubstituted-2-amino-4-oxo-3,4-dihydropyridine bases of this invention may be represented by the following structural formula:

R₁ and R₂ in the above formula each represents an alkyl or alkenyl group.

The compounds of Formula I may be hydrogenated to obtain 3,3-disubstituted-2-amino-4-oxo-3,4,5,6-tetrahydropyridine bases which may be represented by the following structural formula:

R₃ and R₄ in Formula II each represents an alkyl group.

The compounds of both Formula I and Formula II form acid addition salts and these salts are also within the scope of the invention. The compounds of this invention are useful as sedatives and hypnotics. They may be administered orally or parenterally, preferably by incorporating therapeutic doses in tablets or in liquid preparations according to conventional procedures.

R₁ and R₂ in the above formulae represent alkyl or alkenyl groups such as methyl, ethyl, n-propyl, isopropyl, butyl, isobutyl, allyl, isobutenyl, etc. R₃ and R₄ represent similar alkyl groups. The groups represented by R₁ and R₂ or R₃ and R₄ in a given compound may be the same, that is, both substituents may be identical alkyl groups or identical alkenyl groups, or they may be mixed, that is, two different alkyl groups or one alkyl group and one alkenyl group, as the case may be. According to a preferred modification, the alkyl and/or alkenyl groups represented by R₁ and R₂ or R₃ and R₄ together have a

2

total of 2 to 10 carbon atoms. Most preferred are lower alkyl or lower alkenyl groups.

For convenience the groups represented by R₁ and R₂ or R₃ and R₄ in the compounds of Formulae I and II above and the same substituents in the intermediates from which they are derived are sometimes hereinafter referred to as "dialkyl" groups, but this term is an abbreviated form intended to signify the alkyl and alkenyl groups defined in the preceding paragraph.

- 10 The compounds of this invention may be produced in the following manner. A monoalkyl- or monoalkenyl-acetoacetonitrile may be alkylated, for example with an alkyl halide or alkenyl halide, to obtain α,α -dialkyl-acetoacetonitrile. The last named compound is treated with 15 a formic acid ester, such as methyl formate, and with an alkaline condensation agent, such as sodium methylate, then with ammonia to obtain 1,1-dialkyl-1-cyano-2-oxo-4-amino-3-butene. The butene compound is cyclized with an alkali alcoholate, such as sodium methylate, preferably in methanol, to produce 2-amino-3,3-dialkyl-4-oxo-3,4-dihydropyridine. The last named compound is then 20 catalytically hydrogenated to obtain 2-amino-3,3-dialkyl-4-oxo-3,4,5,6-tetrahydropyridine.

Alternatively, a monoalkyl-acetoacetamide may be alkylated and the α,α -dialkyl-acetoacetamide thus obtained is dehydrated with thionyl chloride or phosphorus oxychloride to obtain α,α -dialkyl-acetoacetonitrile which is then further treated as described above.

The cyclization of the 1,1-dialkyl-1-cyano-2-oxo-4-amino-3-butene is preferably effected by the action of an alkali metal alcoholate in the presence of the corresponding alcohol at a slightly elevated temperature. For example, 1,1-dialkyl-1-cyano-2-oxo-4-amino-3-butene may be dissolved in methanol, treated with sodium methylate and then heated to boiling under reflux. The 3,3-dialkyl-2-amino-4-oxo-3,4-dihydropyridine thus formed may be obtained in crystalline form by partially distilling off the alcohol and adding water.

The 3,3-disubstituted-2-amino-4-oxo-3,4-dihydropyridine may, if desired, be reduced to the corresponding 3,3-disubstituted-2-amino-4-oxo-3,4,5,6-tetrahydropyridine. This may be effected, for example, by catalytically hydrogenating the base or its salt, preferably in the presence of a noble metal catalyst, e. g. finely divided palladium. By this procedure unsaturated substituents in the 3-position are hydrogenated to saturated groups. The 3,3-disubstituted-2-amino-4-oxo-3,4,5,6-tetrahydropyridines produced in this manner may be isolated by separating the catalyst from the hydrogenation reaction mixture and evaporating the solvent.

The compounds are strongly basic substances and form acid addition salts with various organic and inorganic acids such as acetic acid, tartaric acid, salicylic acid, the hydrohalic acids, e. g. hydrochloric acid and hydrobromic acid, and other mineral acids such as sulfuric acid, phosphoric acid, etc. Pharmaceutically acceptable acid addition salts constitute a preferred group. The acid addition salts are produced by treating the base with the appropriate acid, preferably in a solvent, e. g. hydrochloric acid in alcohol.

Although the foregoing discussion speaks in terms of only one tautomeric form of the intermediates and final

products represented by the above formulae, the compounds may exist in other tautomeric forms which are also within the scope of the invention. Other tautomeric forms of the compounds may, for example, be formulated as 3,3-disubstituted-2-imino-4-oxo-1,2,3,4-tetrahydropyridine and 3,3-disubstituted-2-imino-4-oxopiperidine, respectively.

The following examples are illustrative of the invention. All temperatures are in degrees centigrade.

EXAMPLE 1

100 g. of diethyl-acetoacetamide were heated with 100 g. of thionyl chloride to boiling under reflux for 20 minutes, then freed in vacuo from most of the thionyl chloride and poured into a mixture of ice and soda solution. The mixture was extracted with ether and the ether solution, after drying over sodium sulfate, was distilled. At first the ether evaporated and the α -diethyl-acetoacetonitrile produced distilled over at 73-76°/13 mm.

770 g. of α - α -diethyl-acetoacetonitrile and 500 g. of formic acid methyl ester were dissolved in 2,000 cc. of toluene and treated portionwise with 316 g. of sodium methylate. The reaction mixture was cooled as required so that the temperature did not exceed 27°. At the end of the reaction, ice water was added, the organic phase was separated and extracted with three 100 cc. portions of 3 N sodium hydroxide. The combined aqueous extracts were treated with 390 g. of ammonium chloride, 70 cc. of 25% aqueous ammonia and 1,000 cc. of benzene and warmed for 75 minutes at 60-70° with vigorous stirring. After cooling, the benzene layer was separated and the aqueous phase was extracted twice with 150 cc. portions of benzene. After evaporating the solvent there remained an oil which quickly solidified. The 1,1-diethyl-1-cyano-2-oxo-4-amino-3-butene obtained in this manner boiled at 137-145°/0.1 mm. After dissolving and crystallizing from petroleum ether, the light yellow crystals melted at 67°.

835 g. of 1,1-diethyl-1-cyano-2-oxo-4-amino-3-butene were dissolved in 700 cc. of warm methanol and treated with 270 g. of sodium methylate with occasional cooling. The dark red colored solution was heated to reflux for 10 minutes and then concentrated to about $\frac{2}{3}$ its volume. The concentrate was cooled with ice water and treated with 1,500 cc. of ice water while stirring vigorously. The 2-amino-3,3-diethyl-4-oxo-3,4-dihydropyridine crystallized in yellow crystals which were difficultly soluble in water. To complete the crystallization, an additional portion of methanol was evaporated from the cold solution, the residue was filtered under suction and washed with ice water. After recrystallization from methanol, the citron yellow crystalline base melted at 201°.

The product obtained above was treated with hydrochloric acid in alcohol. The colorless, crystalline hydrochloride of 2-amino-3,3-diethyl-4-oxo-3,4-dihydropyridine was precipitated with ether, M. P. 180°.

100 g. of the hydrochloride of 2-amino-3,3-diethyl-4-oxo-3,4-dihydropyridine were dissolved in about 800 cc. of methanol and agitated in a hydrogen atmosphere in the presence of about 3 g. of 5% palladium charcoal at room temperature. After the absorption of one mol of hydrogen, the hydrogenation came to an end. The catalyst was separated from the solution which was then concentrated and treated with dry ether. The colorless crystalline hydrochloride of 2-amino-3,3-diethyl-4-oxo-3,4,5,6-tetrahydropyridine melted at 263-264°.

EXAMPLE 2

100 g. of isopropyl-acetoacetamide were dissolved in 100 g. of phosphorus oxychloride, quickly warmed to

100° and poured out onto ice and potassium carbonate solution. The reaction mixture was extracted with ether and the ether solution, after drying with sodium sulfate, was distilled under water vacuum. At first, the ether evaporated, then the isopropyl-acetoacetonitrile distilled over at 78-80°/10 mm.

300 cc. of boiling diethyl carbonate was treated first with 43 g. of sodium methylate and then with 95 g. of isopropyl-acetoacetonitrile. Approximately 50 cc. of the mixture was then distilled off. To the suspension of the sodium salt thus formed, 100 g. of allyl bromide were added. The reaction mixture was refluxed with stirring for a short time, cooled, treated with ice water, separated from the aqueous phase and distilled under water vacuum. The α -allyl- α -isopropyl-acetoacetonitrile thus produced boiled at 87-89°/11 mm.

A mixture of 112 g. of α -allyl- α -isopropyl-acetoacetonitrile, 61 g. of formic acid methyl ester and 200 cc. of benzene were poured into a suspension of 16.3 g. of finely divided sodium in 200 cc. of benzene and stirred for 16 hours. By means of occasional cooling the temperature within the flask was maintained below 28°. The sodium salt of 1-allyl-1-cyano-1-isopropyl-2-oxo-4-hydroxy-3-butene thus formed and water were brought into solution and the phases were separated from each other. The organic phase was washed with approximately 30 cc. of 3 N sodium hydroxide, the combined aqueous extracts were treated with 300 cc. of benzene, 75 g. of ammonium chloride and 20 cc. of concentrated ammonia and the mixture was intensively stirred for 1 $\frac{1}{4}$ hours at 70°. The benzene solution, containing 1-allyl-1-cyano-1-isopropyl-2-oxo-4-amino-3-butene, was separated, dried and concentrated. After the evaporation the residue spontaneously solidified, M. P. 73-74°.

100 g. of 1-allyl-1-cyano-1-isopropyl-2-oxo-4-amino-3-butene were introduced into a solution of 18 g. of sodium and 250 cc. of methanol with stirring. The mixture was refluxed for $\frac{1}{4}$ hour. Then approximately 100 cc. of methanol were permitted to distill off under reduced pressure, the dark colored solution was cooled and treated with 400 cc. of ice water whereupon 2-amino-3-allyl-3-isopropyl-4-oxo-3,4-dihydropyridine precipitated as yellow colored crystals. The melting point of the base, recrystallized from methanol, was 162-163°.

The hydrochloride of 2-amino-3-allyl-3-isopropyl-4-oxo-3,4-dihydropyridine, M. P. 178°, was produced by treating the base with hydrochloric acid in alcohol as described in Example 1.

2-amino-3-allyl-3-isopropyl-4-oxo-3,4-dihydropyridine was dissolved in methanol, treated with 5% palladium charcoal and agitated at room temperature with hydrogen. After one mol of hydrogen was absorbed, the hydrogenation was stopped, the catalyst was filtered off and the methanol solution was concentrated. The residue, 2-amino-3-isopropyl-3-n-propyl-4-oxo-3,4-dihydropyridine, melted at 190-191° after recrystallization from methanol.

The hydrochloride of 2-amino-3-isopropyl-3-n-propyl-4-oxo-3,4-dihydropyridine was produced by the method described above, M. P. 179°.

100 g. of the hydrochloride of 2-amino-3-allyl-3-n-propyl-4-oxo-3,4-dihydropyridine were dissolved in 700 cc. of methanol, treated with approximately 3 g. of 5% palladium charcoal and agitated at room temperature in a hydrogen atmosphere. After two mols of hydrogen were absorbed, the hydrogenation was stopped. The catalyst was separated from the reaction mixture and the solution was concentrated. The hydrochloride of 2-amino-3-isopropyl-3-n-propyl-4-oxo-3,4,5,6-tetrahydropyridine crystallized in colorless needles, M. P. 182°.

Additional compounds represented by Formulae I and II above and salts thereof were synthesized according to the method of Example 2. The melting point or boiling

point of the intermediates and final products obtained are set forth in the following table.

Table

R ₁	R ₂	A	B	C		D	
				Base, M. P. °C.	HCl, M. P. °C.	Base, M. P. °C.	HCl, M. P. °C.
Ethyl	Methyl	B. P. ₁₂ 70-72°	B. P. ₁₄ 161-172°	149	176	233-235	
Methyl	n-Propyl	B. P. ₁₂ 79°	B. P. ₁₄ 152°	140	172	126	154

A = α -R₁- α -R₂-acetoacetonitrile.

B = 1-R₁-1-R₂-1-cyano-2-oxo-4-amino-3-butene.

C = 3-R₁-3-R₂-2-amino-4-oxo-3,4-dihydropyridine.

D = 3-R₁-3-R₂-2-amino-4-oxo-3,4,5,6-tetrahydropyridine.

We claim:

1. A member of the group consisting of bases having the formula

and

wherein R₁ and R₂ each represents a member of the group consisting of alkyl and alkenyl, and R₃ and R₄ each represents alkyl, said groups represented by R₁ and R₂ and by R₃ and R₄ having together a total of 2 to 10 carbon atoms in a given compound,

and pharmaceutically acceptable acid addition salts of said bases.

2. A compound having the formula

25

30

35

40

45

50

3. A compound having the formula

wherein the two alkenyl groups together have a total of 2 to 10 carbon atoms.

4. A compound having the formula

wherein the two alkyl groups together have a total of 2 to 10 carbon atoms.

5. 2 - amino - 3,3 - diethyl - 4 - oxo - 3,4,5,6 - tetrahydropyridine.

6. 2 - amino - 3,3 - di - n - propyl - 4 - oxo - 3,4 - dihydropyridine.

7. 2 - amino - 3,3 - diallyl - 4 - oxo - 3,4 - dihydropyridine.

8. 2 - amino - 3,3 - di - n - propyl - 4 - oxo - 3,4,5,6 - tetrahydropyridine.

No references cited.

wherein the two alkyl groups together have a total of 2 to 10 carbon atoms.
